FILTER CIGARETTE HOLDER

Henrietta M. Nagle, New York, N. Y.

Application May 31, 1955, Serial No. 512,126

3 Claims. (Cl. 131—182)

This invention relates to improvements in smoking articles and the like.

An object of the invention is to provide a novel and improved cigarette holder which is engageable with a cigarette in such a manner as to make it a filtered cigarette.

Another object of the invention is to provide a novel and improved cigarette holder which includes means for effecting compression of the tobacco in a portion of the cigarette, so that the compressed tobacco of the cigarette forms a filter for smoke, nicotine and tars, and other products of the smoking process.

A further object of the invention is to provide a novel and improved cigarette holder in which there is an opening for the reception of an end of a cigarette, and a slideable cigarette penetrating member which is disposed inside the housing of the holder, and adapted for being extended forwardly so as to penetrate into the tobacco at the rearward end of the cigarette, thus expanding the tobacco outwardly radially, and compressing the tobacco, the arrangement being such that the smoke which flows rearwardly through the cigarette on puffing by the smoker, is constrained to flow through the compressed tobacco, and thus to be filtered thereby.

Still another object of the invention is to provide a novel and improved filter type cigarette holder in which the cigarette itself is made to become a smoke filter, by having the rearward end of the cigarette confined in a cylindrical housing, so that it cannot expand, and including an elongated shaft of substantial thickness which is carried on a smoke permeable support within the holder housing, the support being extensible forwardly so that its elongated shaft is pushed into the confined end of the cigarette, and of sufficient thickness or radial dimension as to provide substantial radial compression of the tobacco, the shaft being constructed to block passage of smoke therethrough, so that the smoke must pass through the tobacco which is compressed, and is thus filtered.

These and other objects and advantages of the invention will become apparent from the following description of a preferred embodiment thereof, as illustrated in the accompanying drawings, forming a part hereof, and in which,

Figure 1 is an elevational view of a cigarette holder according to the invention, with a cigarette disposed therein.

Figure 2 is a sectional elevational view taken substantially on plane 2—2 of Figure 1, the movable internal elements being shown in retracted dispositions.

Figure 3 is a transverse sectional elevational view taken substantially on plane 3—3 of Figure 2.

Figure 4 is a transverse sectional elevational view taken substantially on plane 4—4 of Figure 2.

Figure 5 is a detail plan view of the cigarette penetrating housing and shaft apart from the assembly.

Figure 6 is a detail plan view of the cigarette ejecting housing apart from the assembly.

2

Figure 7 is a fragmentary longitudinal sectional elevational view taken on the same plane as Figure 2, but showing a modified form of construction with a replaceable threaded shank member at 72b.

In connection with the smoking of cigarettes, it has become increasingly apparent that the public to a large extent, finds certain advantages in filtration of the smoke before it reaches the mouth and lungs of the smoker. Such filtration has heretofore been accomplished mainly by introduction of a filter tip to the rearward end of the cigarette, which contains cellulose, cotton fibres, or other filtering material which is not of the same material as the tobacco itself. The present invention provides means whereby the ordinary unfiltered cigarette may be its own filter, and thus avoids the need for attachment of filter tips to the cigarette, or for use of other auxiliary filtering materials in the path of the smoke. This is done by compressing the tobacco in the rearward end portion of the cigarette, and thus constraining the smoke to flow through the compressed tobacco, taking advantage of its high degree of smoke filtering action. A housing is provided, into which the rearward end of the cigarette is inserted to a substantial degree, and a movable penetration shaft is movably mounted inside the housing, so that on forward movement it penetrates into the tobacco and thus compresses it radially outwardly. The smoke must flow through the compressed tobacco, and is thus filtered. After smoking, the butt is ejected by simple movable means.

The present invention thus provides for many advantages in cigarette filtering, without need for complicated structural means or addenda to the cigarettes themselves for bringing this about. In order to understand clearly the nature of the invention, and the best means for carrying it out, reference may now be had to the drawings, in which like numerals denote similar parts throughout the several views.

As shown, there is a main cigarette holder housing generally indicated at 20, which in the form shown may be generally cylindrical, tapering at its rearward end portion to the left of location 26, to form a mouthpiece 28, the tip of which is seen at 30. The mouthpiece 28 has a passageway 32 formed therethrough, which opens upon the main bore 24 of the main housing, and from Figures 1 and 2, it is seen that a cigarette 10 may have its rearward end portion inserted into the forward opening 16 of the main housing for a substantial distance inwardly of the forward end 18 of the main housing.

Inside the main housing bore 24 are two main assemblies or members, namely the cigarette ejector member 50, shown in detail also in Figure 6 apart from the assembled device, and the tobacco penetrator-compressor member 52. The cigarette ejector member 50 has a cylindrical body wall 62 secured at its forward end to the forward wall 63, and open at its rearward end, thus defining a cylindrical bore 65 in which is slidably disposed the cylindrical body wall 53 of the penetrator-compressor member 52.

As seen best in Figures 2 and 4, the front wall 63 of the ejector member 50 has a number of openings 66 formed therein to allow passage of air and smoke therethrough as indicated by the arrows in Figure 2, the openings 66 being formed between the spider legs or ribs 64 remaining and the central wall portion or hub 63. A position adjusting knob 58 is mounted on the pin 60 which in turn is seated in a socket formed in the wall 62 of the ejector member so as to be movable therewith. As seen best in Figures 1, 2 and 4, the pin 60 is constrained to movement in the guide slot 92 formed in main outer housing 22, from a rearward position at which the cigarette is insertable in the holder, to full forward position at which the cigarette is ejected from the holder, when the burning at 11 has progressed

for a sufficient time, or the user is finished with smoking it.

The cigarette compressor-penetrator member 52 also has a cylindrical body wall 53 the outside diameter of which is substantially the same as the inside diameter of the ejector bore 65, with only sufficient looseness to permit easy slidable movement of the two members 52 and 50 on each other without slippage. The member 52 also has a forward wall 57, provided with openings 84 between the spider ribs 86 and the central area or hub 88, for the free passage of air and smoke as indicated by the arrows in Figure 2. The rearward end of member 52 is open, to allow air and smoke to pass therethrough. A cigarette penetrator-expander or compressor shaft 72 is carried on the forward wall of member 52, being either integral therewith, or mounted in any convenient manner, as by having its reduced rearward end 74 extending through an opening in the hub area 88 of the wall 57, and then peened over as shown to retain the shaft 72 for movement with member 52.

The forward end 73 of the tobacco compressor shaft 72, may be conveniently pointed to facilitate its entry into and expansion of the tobacco in the rearward end of the cigarette when it is moved to forward position, as shown by broken lines at 72a in Figure 2. A knob 56 is mounted on a pin 54 seated in the wall 53 of the expander member 52, and extends through the motion limiting guide slot 94 formed in wall 22 of the outer housing, to permit easy adjustment of the position of the member 52. The length of the slot 94 is chosen to give the desired degree of penetration of the shaft 72 into the cigarette. As seen, there is a central opening 70 in the front hub area 68 of the ejector 50, to allow the pin shaft 72 to slide therethrough, and to aid in maintaining its axial orientation at all times.

In using the device, with the members 52 and 50 in retracted positions, as shown in Figure 2, the cigarette is inserted inside the front or ferrule portion 18 of the main housing, so that a substantial portion of the cigarette length is confined inside ferrule portion 18 as shown. The knob 56 which is the cigarette compressor actuating knob, is then pushed forwardly, causing the expander shaft 72 to enter the tobacco 14 of the cigarette, displacing the tobacco radially outwardly as the shaft moves to position 72a, and thus compressing the tobacco in the annular space between the shaft 72a and the ferrule 18, and forming a long annular mass of densely packed tobacco rearwardly of location 16. The cigarette is then lighted as at 11, and it is apparent that the smoke must travel rearwardly through the more densely packed annular tobacco mass under ferrule 18, since the shaft 72 remains in the tobacco, and hence a considerable filtering action is obtained, the tobacco being more dense giving good filtration by blocking passage of impurities in the smoke, and holding them within itself. It is noted that the smoke can pass freely rearwardly due to the openings 66 and 84. After the cigarette is smoked, it is simple to retract the knob 56, pulling out the shaft 72, and to push forward the ejecting knob 58, moving member 50 forwardly, and ejecting the smoked cigarette from the holder. The ferrule 18 permits of good radial displacement of the tobacco by shaft 72, since there is support by ferrule 18 to hold the displaced tobacco.

For obtaining further or adjustable filtration, it is possible to increase or decrease the degree of insertion of the shaft 72 in the cigarette, and also by further insertion of the cigarette in the holder, or lessening the insertion. By making the shaft 72 quite long, and the ferrule 18 correspondingly long, the degree of filtration due to increased length of filtration path can be made of any degree at all as desired. Similarly, as shown in Figure 7, the shaft 72b may be made to thread at 73b into the central opening 71 in wall 57, and easily removable so that the dealer may sell it with several lengths of differing size of such shaft, to suit the needs of the smoker.

Also the diameter of the shaft 72 may be made in varying sizes, so that a higher or lower degree of radial displacement may be obtained to suit the smoker.

Although I have described my invention in specific terms, it will be understood that various changes may be made in size, shape, materials and arrangement without departing from the spirit and scope of the invention as claimed.

I claim:

1. A smoking device comprising a main tubular housing having a bore formed therethrough, said housing being reduced at its rearward end to form a mouthpiece, a forward end portion of said main tubular housing delineating a ferrule for receiving a substantial tobacco containing rearward end portion of a cigarette, a tubular cigarette ejecting means slidably engaging said main housing bore, said main housing having a slot, actuating pin and knob means carried by said ejecting means and extending through said slot for allowing forward and rearward motion of said ejecting means for ejecting said cigarette from said housing as desired, said ejecting means having an ejecting means bore formed therein, tubular shaft support means slidably engaging said ejecting means bore for forward and backward movement therein, a tobacco expanding shaft means carried by said tubular shaft support means and extending forwardly thereof, said ejecting means having an opening through which said shaft means is extensible forwardly of said ejecting means, whereby on forward movement of said shaft means it penetrates into the said tobacco within said ferrule, compressing it outwardly and forming an annular compacted mass of tobacco for filtering purposes, through which smoke is constrained to flow, and means accessible from outside said main housing for moving said shaft support means and said shaft forwardly and backwardly, for smoking either with or without filtration as desired.

2. A smoking device comprising a main housing having a passage formed therein, a tobacco compressing shaft, and a shaft support means carrying said shaft and disposed movably in said passage, and constructed and arranged so that said shaft is movable forwardly for penetration of a rearward mass of tobacco in a cigarette extending inside said main housing, whereby the said mass of tobacco is radially outwardly compressed by said shaft and whereby an annular plug of dense tobacco is formed into a filter, and wherein said shaft support means comprises a hollow tubular support body, and spider means carried by said support body and constructed and arranged for engaging said shaft, whereby smoke is free to flow through said hollow tubular support body and said spider means.

3. A smoking device comprising a main housing having a passage formed therein, a tobacco compressing shaft, and a shaft support means carrying said shaft and disposed movably in said passage, and constructed and arranged so that said shaft is movable forwardly for penetration of a rearward mass of tobacco in a cigarette extending inside said main housing, whereby the said mass of tobacco is radially outwardly compressed by said shaft and rendered more dense than prior to insertion of said shaft, whereby an annular plug of dense tobacco is formed into a filter, and wherein said shaft support means comprises a hollow tubular support body, spider means carried by said support body and constructed and arranged for engaging said shaft for movement therewith, and having a plurality of openings formed in said spider means, whereby smoke is free to flow past said shaft and through said spider means and hollow support body, and positioning means including a knob and a pin securing said knob to said hollow tubular support body, said pin extending through said main housing, and said main housing having a slot means therethrough for receiving said pin and oriented for permitting forward and rearward movement of said pin in said slot, whereby, by movement of said knob outside said main housing, said tobacco expanding shaft is movable forwardly to compress tobacco in a cigarette.

rette, and rearwardly out of such compressing position as desired.
